UNITED STATES PATENT OFFICE.

JACOB BERNHARD MOSES, OF DALLAS, TEXAS.

HOLDER FOR SOUND-RECORD TABLETS.

968,253.

Specification of Letters Patent. Patented Aug. 23, 1910.

Application filed August 7, 1909. Serial No. 511,804.

To all whom it may concern:

Be it known that I, JACOB BERNHARD MOSES, a citizen of the United States, residing at Dallas, in the county of Dallas and State of Texas, have invented a new and useful Holder for Sound-Record Tablets, of which the following is a specification.

This invention has reference to improvements in holders for sound record tablets and its object is to provide a cabinet especially adapted for use with sound record tablets of square form and also includes jackets or envelops adapted to contain individual tablets and also insertable into the cabinet.

The invention will be best understood from a consideration of the following detail description taken in connection with the accompanying drawings forming a part of this specification, in which drawings,

Figure 1 is a perspective view of a cabinet especially adapted for square tablets, parts being broken away and shown in section. Fig. 2 is a detail view illustrating means for adjusting parts of the cabinet. Fig. 3 is a central vertical section of the cabinet of Fig. 1 on a smaller scale. Fig. 4 is a detail view of another form of support for the tablets within the cabinet. Fig. 5 is a face view of one form of tablet. Fig. 6 is a cross section of the same. Fig. 7 is a face view of another form of tablet. Fig. 8 is a container for an individual tablet also indicating still another form of tablet. Fig. 9 is a view of a different form of container than that shown in Fig. 8.

Referring first to Figs. 5, 6, 7 and 8 there is shown in Fig. 5 a tablet 1 square in outline and having a circular zone 2 designed to receive the sound record groove. In Fig. 7 the corners of the tablet are shown rounded instead of at right angles as shown in Fig. 5.

Exterior to the sound record receiving zone 2 the tablet is provided with a label 3 occupying the corners of the square tablet exterior to the circular zone 2. The tablet is provided with a sound record impression on either or both faces and when both faces are provided with a sound record impression then the label on each side may contain the titles of both records.

The tablets may be readily inserted in square envelops such as indicated at 4 in Figs. 8 and 9, these envelops having the open or mouth end cut away from the cen-

ter toward the edges on both faces as indicated at 5 in Fig. 8 or on one side as indicated at 6 in Fig. 9, the outer side 7 extending to the edge or beyond the edge of the tablet. One side of the envelop may be provided with a flap 8 below which is formed a slot 9, as indicated in Fig. 8, or the flap may be omitted as indicated in Fig. 9 while the other side of the envelop is provided with a locking flap adapted to override the exposed edge of the tablet and be inserted in the slot 9, thus closing the envelop against accidental opening.

The square form of tablet is especially adapted for use in connection with a cabinet illustrated in Figs. 1 and 3 where there is shown a case 10 having therewithin a slanting partition 11 forming a floor or rack for the tablets. Secured to each side of the case 10 in opposition one to the other are grooved strips 12, the grooves being arranged in matched relation so that two grooves on opposite sides of the casing will receive the opposite edges of a tablet or of an envelop 4 containing a tablet.

Usually the cabinets are made for standard ten inch records but they may be made for the larger, twelve inch size record, and provision may then be made for the holding of the smaller record by making the grooved strips 12 in sections and adjustable one toward the other.

In Fig. 2 there is shown a grooved strip 12' held to the wall of the casing 10 by means of an adjusting screw 13 accessible from the exterior of the casing and so arranged that the strip 12' may be moved away from the inner face of the casing toward the other face thereof to reduce the distance between the strips. By this means a portion of the strip 12 may be made permanently attached to the sides of the casing 10 in such position as to readily receive 12 inch record tablets while other sections 12' may be made adjustable for receiving tablets of less diameter, say tablets of 10 inches in diameter. The cabinet may be made with the top and a portion of the front hinged together with the top hinged to the casing so that a portion of the front and the top may be folded back out of the way thus exposing the interior of the casing to access. In this case, for ornamental purposes, the front may contain a transparent panel so that the labels on the records may be read at any time. If it be not desirable

to read the labels then any protecting means may be attached to the inside of the cabinet to protect the tablets from the action of dust or dirt.

5 Because of the inclined partition 11 there is more or less space remaining below this partition and this may be utilized for various purposes, access to the space being obtainable through a suitable door 14. Of course a space below the partition 11 may 10 also contain a drawer 15.

By arranging the strips 12 and partition 11 in inclined relation to the horizontal or to the bottom of the cabinet each tablet will 15 project a short distance above the next succeeding tablet toward the front of the casing or cabinet. The labels on the upper corners of the tablets will therefore all be 20 visible to an observer standing in front of the cabinet and any one or more of the tablets may be readily chosen without the necessity of touching these tablets and because of the large label surface and the possibility of placing the titles of both the face 25 and reverse side of the tablet upon one face the entire series of selections upon both faces of all the tablets may be observed at one time without the necessity of lifting the tablets from their support as is necessary 30 with the circular form of tablets having the labels at the center. It is because of this facility of observation that the square tablet is especially adapted for use in connection 35 with a cabinet such as shown in Figs. 1 and 3.

In Figs. 1 and 3 the grooved strips 12 are shown as made of wood or similar material with the groove formed therein.

In Fig. 4 there is shown a small section of a metal strip bent on itself to form 40 grooves or receptacles for the edges of the tablets and such strips may replace the strips 12.

What is claimed is:

1. A cabinet for sound record tablets provided with a slanting floor for supporting tablets and a slanting series of upright channel strips for holding the tablets in spaced spread count order, said strips being adjustable with relation to the respective side 50 of the cabinet for movement toward and from mating strips, and means for adjusting and holding said adjustable strips in adjusted positions.

2. A cabinet for sound record tablets provided with channel strips for receiving the tablets on diametrically opposite sides, part of said strips being in fixed relation to mating strips and others of said strips being in adjustable relation to the mating strips 60 for movement toward and from each other, and means for moving said strips and locking them in adjusted position.

In testimony that I claim the foregoing as my own, I have hereto affixed my signature in the presence of two witnesses.

JACOB BERNHARD MOSES.
